(57) **CLAIM**

The ornamental design for a sleeve container for cosmetic sachets as shown and described.

DESCRIPTION

FIG. 1 is a front left side perspective view showing the new design for sleeve container for cosmetic sachets in a closed orientation;

FIG. 2 is a front right side perspective view thereof taken from underneath the sleeve container;

FIG. 3 is a rear right side perspective view thereof taken from underneath the sleeve container;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a front left side perspective view showing the sleeve container for cosmetic sachets from FIG. 1 in an open orientation and showing cosmetic sachets as held in the sleeve container;

FIG. 11 is a front right side perspective view thereof taken from underneath the sleeve container;

FIG. 12 is a rear right side perspective view thereof taken from underneath the sleeve container;

FIG. 13 is a front top side perspective view thereof;

FIG. 14 is a front view thereof;

FIG. 15 is a rear view thereof;

FIG. 16 is a left side view thereof;

FIG. 17 is a right side view thereof;

FIG. 18 is a top plan view thereof;

FIG. 19 is a bottom plan view thereof;

FIG. 20 is a front left side perspective view showing the sleeve container for cosmetic sachets from FIG. 10 in an open orientation and with a cosmetic sachet being removed therefrom;

FIG. 21 is a front side perspective view thereof taken from underneath the sleeve container;

(Continued)

FIG. 22 is a front view thereof;
 FIG. 23 is a rear view thereof;
 FIG. 24 is a left side view thereof;
 FIG. 25 is a right side view thereof;
 FIG. 26 is a top plain view thereof;
 FIG. 27 is a bottom plan view thereof;
 FIG. 28 is a front left side perspective view showing the sleeve container for cosmetic sachets from in an open orientation and in accordance with another embodiment of the application;
 FIG. 29 is a front right side perspective view thereof taken from underneath the sleeve container;
 FIG. 30 is a rear right side perspective view thereof taken from underneath the sleeve container;
 FIG. 31 is a front top side perspective view thereof;
 FIG. 32 is a front view thereof;
 FIG. 33 is a rear view thereof;
 FIG. 34 is a left side view thereof;
 FIG. 35 is a right side view thereof;
 FIG. 36 is a top plan view thereof;
 FIG. 37 is a bottom plan view thereof;
 FIG. 38 is a front left side perspective view showing the new design for sleeve container for cosmetic sachets in a closed orientation and in accordance with another embodiment of the present invention;
 FIG. 39 is a front right side perspective view thereof taken from underneath the sleeve container;
 FIG. 40 is a rear right side perspective view thereof taken from underneath the sleeve container;
 FIG. 41 is a front view thereof;
 FIG. 42 is a rear view thereof;
 FIG. 43 is a left side view thereof;
 FIG. 44 is a right side view thereof;
 FIG. 45 is a top plan view thereof;
 FIG. 46 is a bottom plan view thereof,
 FIG. 47 is a front left side perspective view showing the sleeve container for cosmetic sachets from FIG. 38 in an open orientation and showing cosmetic sachets as held in the sleeve container;
 FIG. 48 is a front right side perspective view thereof taken from underneath the sleeve container;
 FIG. 49 is a rear right side perspective view thereof taken from underneath the sleeve container;
 FIG. 50 is a front top side perspective view thereof;
 FIG. 51 is a front view thereof;
 FIG. 52 is a rear view thereof;
 FIG. 53 is a left side view thereof;
 FIG. 54 is a right side view thereof;
 FIG. 55 is a top plan view thereof;
 FIG. 56 is a bottom plan view thereof,

FIG. 57 is a front left side perspective view showing the sleeve container for cosmetic sachets from FIG. 47 in an open orientation and showing cosmetic sachets as held in the sleeve container;
 FIG. 58 is a front right side perspective view thereof taken from underneath the sleeve container;
 FIG. 59 is a rear right side perspective view thereof taken from underneath the sleeve container;
 FIG. 60 is a front top side perspective view thereof;
 FIG. 61 is a front view thereof;
 FIG. 62 is a rear view thereof;
 FIG. 63 is a left side view thereof;
 FIG. 64 is a right side view thereof;
 FIG. 65 is a front left side perspective view showing the sleeve container for cosmetic sachets from in an open orientation and in accordance with another embodiment of the application;
 FIG. 66 is a front right side perspective view thereof taken from underneath the sleeve container;
 FIG. 67 is a rear right side perspective view thereof taken from underneath the sleeve container;
 FIG. 68 is a front top side perspective view thereof;
 FIG. 69 is a front view thereof;
 FIG. 70 is a rear view thereof;
 FIG. 71 is a left side view thereof;
 FIG. 72 is a right side view thereof;
 FIG. 73 is a top plan view thereof; and,
 FIG. 74 is a bottom plan view thereof.
 The broken lines shown illustrate portions that form no part of the claimed design.
